UNITED STATES PATENT OFFICE.

ALEXANDER LEON HATZAN, OF NIAGARA FALLS, ONTARIO, CANADA.

RUPTURE APPLIANCE.

1,389,047.

Specification of Letters Patent. Patented Aug. 30, 1921.

Application filed August 9, 1920. Serial No. 402,249.

To all whom it may concern:

Be it known that I, ALEXANDER LEON HATZAN, a citizen of the Dominion of Canada, residing at Niagara Falls, in the county 5 of Welland and Province of Ontario, Canada, have invented certain new and useful Improvements in Rupture Appliances, of which the following is a specification.

This invention relates to improvements in 10 rupture appliances, and the objects of the invention are to construct the appliance so that it will readily fit ordinary sized persons, and capable of being used on either the right or left side, the appliance being 15 self adjusting, to render the appliance unencumbered, imperceptible in wearing, easily placed in position and removed, capable of being worn without inconvenience both day and night and whether at work or play. 20 In order to give an understanding of my invention, I have illustrated in the drawings a selected embodiment thereof, which will now be described, after which the novel features will be pointed out in the appended 25 claim.

In the drawings, Figure 1 shows the figure of a man wearing my improved rupture appliance.

Fig. 2 is a perspective view of my improved rupture appliance.

Fig. 3 is a vertical section through the pad.

Like symbols indicate similar parts throughout the drawings.

Referring to the drawings, A represents 35 my improved rupture appliance comprising a rubber pad 10, the inner wall of which is convex as shown in Fig. 3, and this pad is lined and covered with chamois leather as 40 shown at 11, and the outer face of the pad is flat.

A rubber band 12 reaches from end to end 45 of the rubber pad and is located on the outer flat face thereof and the lower end of the rubber band 12 extends about three inches beyond the rubber pad 10 and is attached to one end of the leg band 13.

This leg band is formed of non-elastic 50 webbing or silk or other like material, and is provided with sliding cleats 14 which permit of the length of the band being adjusted to suit the size and requirements of the person wearing the appliance, and the looped

portion of the leg band is provided with a terminal 15 formed with self fasteners. 55

The upper end of the rubber band 12 is attached to one end of the waist band 16 which is formed of non-elastic webbing, silk or like suitable material, and the other end of the waist band is looped and provided 60 with an adjustable cleat 17.

The looped end of the waist band 16 is provided with a terminal 18 having self fasteners thereon. The rubber band 12 is secured intermediate of its length by a 65 clamping member 19 to the outer flat face of the rubber pad 10.

When the appliance is being used, the rubber pad is placed in position over the rupture, and the leg band 13 then passed under 70 the leg, around the back and over the front when the terminal 15 is secured to the upper portion of the rubber band 12.

The waist band 16 is now placed around 75 the waist just over the hips and the terminal 18 is then engaged with the lower portion of the rubber band 12.

The rubber band will give the desired amount of resiliency and allow the appliance to remain in position while giving every 80 freedom of movement to the wearer, and the adjustment of the straps can be made quickly and effectively to suit the requirements of the user.

What I claim as my invention is: 85

An appliance of the character described, comprising a rubber pad having its inner wall convex, and its outer face flat, an elastic band extended from end to end of said pad on the flat face thereof with one end extended beyond the pad, a leg band attached to said extended end, and formed of non-elastic material, said leg band having a looped portion with a terminal with fasteners, and a waist band formed of non-elastic material 90 with one end attached to said elastic band and the other end looped and provided with a terminal with fasteners, and a clamping member securing the elastic band intermediate its ends to said pad. 95

In testimony whereof I affix my signature in the presence of two witnesses.

A. LEON HATZAN.
